UNITED STATES PATENT OFFICE.

SYDNEY JAMES FLEMING, OF VANCOUVER, BRITISH COLUMBIA, CANADA.

CLOTHESLINE-PULLING CLUTCH.

1,388,455.

Specification of Letters Patent. Patented Aug. 23, 1921.

Application filed October 19, 1920. Serial No. 417,996.

To all whom it may concern:

Be it known that I, SYDNEY JAMES FLEMING, a subject of the King of Great Britain, and a resident of the city of Vancouver, in the Province of British Columbia, Canada, have invented certain new and useful Improvements in Clothesline-Pulling Clutches, of which the following is a specification.

My invention relates to improvements in clothes line pulling clutches, and the object of my invention is to provide a device capable of being attached to a clothes line the use of which enables the line to be operated without touching it with the hand, which device insures a strong and positive grip being obtained and which is of great utility and convenience, while at the same time being simple of construction and cheap to manufacture and sell.

20 I attain this object by the construction illustrated in the accompanying drawings in which—

Figure 1 is a perspective view of my device.

25 Fig. 2 is a view in part section.

Fig. 3 is an end view.

Fig. 4 is a detailed view of the spring clip.

Similar figures of reference indicate similar parts throughout the several views.

The device consists of a metal plate indicated generally by the numeral 1 doubled over into substantially U-shape the space between the sides 2 and 3 of which is sufficient to allow the plate to straddle freely the clothes line 4 when placed thereon in an inverted position. Adjacent one end of the plate holes 5 and 6 are formed in the sides opposite each other while adjacent the other end oppositely disposed slots 7 and 8 are provided, these holes and slots being positioned so that the ends 14 and 15 of a spring clip member 9 passed through them will engage the under side of the clothes line, as shown in Figs. 1 and 3, the spring clip 9 being doubled over at mid-length, as at 10, to form a pin adapted to be passed freely through the oppositely disposed openings 11 formed in the sides 2 and 3 adjacent their lower edges and intermediate the length of the plate as shown in the Figs. 3 and 4. 12 indicates a plate pivotally mounted between the sides 2 and 3 on the pin 10 the upper edge of which plate lies normally close to the clothes line while its lower end is ex-

tended and provided with a suitable gripping handle 13.

The manner in which the device operates and its utility may be briefly described as follows: When assembled and free of the clothes line the parts are as shown in Figs. 1 and 3. To place it on the clothes line the spring clip is withdrawn from the hole 5—6, slots 7—8, and the holes 11 so as to allow the plate 12 to be separated from the U-shaped member 1, after which this latter member is placed over the line and the parts reassembled, it being necessary to press down slightly the arm of the clip which carries the end 15 to depress the end in the slots 7—8 to enable it to be passed through under the line since the upper edges of the slots are above the same from which it will be seen that the end 15 presses upwardly against the line, this pressure being sufficient to maintain the device in the position to which it may be moved thereon. The clutch being thus mounted, the line may be pulled in either direction by gripping the handle 13 and swinging it slightly in the direction in which it is desired to move the line, thus raising the plate 12 at one end and gripping the line between it and the member 1, enabling it to be pulled when desired without direct hand contact.

From the foregoing it will be seen that I have devised a simple and practical line pulling clutch which is of great utility and convenience.

What I claim as my invention is:—

1. A clothes line pulling clutch comprising a substantially U-shaped member adapted to be placed on the line in an inverted position and provided at its opposite ends and intermediate its length with oppositely disposed apertures, the end apertures being positioned just below the line and the intermediate ones adjacent its lower edge, a plate disposed between the sides of the U-shaped member the upper edge of which lies close to the line having an opening registering with the intermediate apertures, the said plate being provided with a gripping handle, and a wire member doubled over intermediate its length forming a pin adapted to pass through the plate opening and the intermediate apertures to pivotally connect said plate and said member the ends of the wire being bent and passed through the said end apertures.

2. A clothes line pulling clutch comprising a substantially U-shaped member adapted to be placed on the line in an inverted position and provided at its opposite ends 5 and intermediate its length with oppositely disposed apertures the apertures at one end being positioned just below the line and those at the opposite end being slotted with the upper edge above the under side of the 10 line, the intermediate apertures being positioned adjacent its lower edge, a plate disposed between the sides of the U-shaped member the upper end of which lies close to the line having an opening registering with 15 the intermediate apertures, said plate being provided with a gripping handle, and a spring wire member doubled over intermediate its length forming a pin adapted to pass through the plate opening and the intermediate apertures to pivotally connect said 20 plate and said member, the ends of the wire being bent and passed through the said end apertures and slots.

3. A clothes line pulling clutch comprising pivotally connected clamping members 25

and additional line engaging means carried by the pivot connecting said clamping members adapted to maintain the clutch in any position on the line to which it may be moved

30

4. A clothes line pulling clutch comprising pivotally connected clamping members, and a resilient line engaging arm carried by the pivot connecting said members and adapted to maintain the clutch in any position on the line to which it may be moved.

35

5. A clothes line pulling clutch comprising a line engaging plate, a clamping member coacting therewith, a pivot passing through said plate and clamping member, 40 an arm carried by the pivot pin and passing through the plate to hold the pin against rotation, and a second arm carried by the pin disposed for engagement with the line to prevent inadvertent movement of the clutch 45 on the latter between line shifting operations.

Dated at Vancouver, B. C., Canada, this
11th day of October, 1920.

SYDNEY JAMES FLEMING.
